(57) **CLAIM**

The ornamental design for a charge cradle, as shown and described.

DESCRIPTION

FIG. 1 is a front perspective view of an ornamental design for a charge cradle;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in FIGS. 1-8, that are immediately adjacent to the shaded areas, and define unshaded regions, represent the bounds, while all other broken lines are directed to environment and are for illustrative purposes only.
